By Richard B. Owen Attorney

UNITED STATES PATENT OFFICE.

LAWRENCE GENNUSA, OF CHICAGO, ILLINOIS.

TOY STEAMBOAT.

Application filed November 26, 1923. Serial No. 677,116.

This invention relates to a toy steam boat and has for its principal object to provide a boat of this nature having a simple construction which may be manufactured at a comparatively low cost yet will be durable and afford considerable amusement to the young.

Another important object of the invention is to provide novel and efficient propulsion means for the toy boat.

A still further important object of the invention is to provide a rudder with means whereby it may be held at various angles in relation to the boat so as to guide the same as may be desired.

With the above and other objects in view as will appear as the description progresses, the invention resides in certain novel features of construction, and in the combination and arrangement of parts as will be hereinafter more fully described and claimed.

In the drawing:

Figure 1 is a side elevation of the boat embodying my invention showing a portion thereof broken way so as to disclose the propulsion mechanism disclosed therein.

Figure 2 is a transverse section through the boat.

Figure 3 is a detail plan view of the rear process of the boat.

Referring to the drawing in detail it will be seen that 1 designates the hull of the boat which may be of any hollow construction 35 having its rear end shaped to overhang as shown at 2. A rudder 3 is carried by a rod 4 suitably journaled through the rear end of the boat so as to extend vertically thereof and terminates at its upper end 40 in a horizontal extension 6 having a rigid depending lug 7 on its terminal. An arcuate shaped plate 8 is mounted on the rear upper end of the boat and is provided with a plurality of apertures to be engaged by the lug 7 so that the rudder 3 may be held at any desired adjusted angle in relation to the boat. As shown, the elements 4, 6 and 7 are formed of a single piece of material so that no removable parts are provided which 50 might become detached or lost. The release of the lug 7 from and engagement of the same with the apertures of plate 8 may be permitted either by making the part 6 manually flexible relative to rod 4 or permitting 55 the entire unit composed of parts 4, 6 and 7 to move vertically a slight distance.

A boiler or water container 9 is mounted on the upper ends of legs 10 secured within and on the bottom of the hull 1 and a suitable burner 11 is disposed and retained on the bottom of the hull under the boiler, so that steam may be generated. A pipe 12 leads from the top of this boiler 9 in the hull 1 so as to extend through the lower rear portion of the latter immediately below and centrally between the sides of the overhanging rear end portion for delivering the steam generated in the boiler rearwardly at the rear of the boat so that when said steam impinges against the water it will cause the boat to move forwardly. Furthermore this steam will heat the water in the immediate vicinity in the rear of the boat and said water having a tendency, after being heated, to rise, will engage the overhanging portion 2 and thereby aid in the forward propulsion of the boat.

It is thought that the construction and operation of the toy should now be understood without any more detail description thereof. It is desired, however, to point out that numerous changes in the details of construction and in the combination and arrangements of parts may be resorted to without departing from the spirit or scope of the invention or sacrificing any of its advantages.

Having thus described my invention what I claim as new is:

1. A toy boat comprising, in combination, 90 a hull having an overhanging upper stern portion, a steam boiler supported with the hull above the bottom of the latter, a burner within the hull beneath the boiler, and a pipe having an open forward end communicating with the interior of the upper portion of the boiler, said pipe further having an open rear end projecting rearwardly through the lower stern portion of the hull midway between the sides of the latter and terminating at the forward end of the overhanging upper stern portion, whereby a jet of steam is discharged rearwardly from the rear end of the pipe coincident with the longitudinal center of the hull and beneath the longitudinal center of said overhanging upper stern portion upon generation of steam in said boiler, said pipe extending downwardly from the boiler to the bottom of the hull and then extending rearwardly 100 within the hull upon the bottom of the latter.

2. In a toy boat, a rudder, a rod journaled vertically through the rear end of the boat and supporting the rudder on the lower end thereof, a horizontal integral extension on the upper end of the rod, a depending lug on the terminal of and rigid with said extension, and an arcuate strip-like plate fixed in a horizontal position upon the top of the boat and provided with a longitudinal series of spaced apertures for selective reception of said lug, said extension and said lug being vertically movable for permitting manual engagement and disengagement of the lug in and from said apertures, whereby said rudder may be adjusted to and held in various positions relative to the longitudinal axis of the boat.
3. In testimony whereof I affix my signature.
